RADIO RECEIVING SYSTEM

Application filed January 13, 1926. Serial No. 81,129.

This invention relates to radio receiving sets and is particularly directed to the radio frequency portion thereof. It is recognized that the physical confines of a receiving set 5 more or less of necessity pre-supposes a loose coupling between the coils going to make up the various resonating circuits that is, between the coils of different stages. It is an object of this invention advantageously to employ this loose coupling between the coils of 10 the resonating circuits for purposes of regeneration. It is, however, a further object to compensate or adjust this loose coupling in such a way that as the set is tuned to receive 15 broadcasting at different wave lengths, the most desirable adjustment may be had for one wave length as well as for another. In simpler language it is also an objective to eliminate that degree of oscillation producing squeals, while at the same time providing 20 for extremely sharp tuning.

In understanding this invention, it should be borne in mind that it is contemplated that the coils referred to are the antenna coil involved in a local circuit tuned by a variable condenser and the secondary coils of the interstage radio frequency coupling transformer likewise adapted to be tuned by a variable condenser. In the embodiment of 25 the invention illustrated, wherever there is a primary associated with one of these secondary coils, its coupling therewith is fixed. A preferred construction comprises two telescoping tubes nested together, the inner 30 carrying the primary winding and the outer tube carrying the secondary coil. The automatically adjusted variable coupling forming an important factor of this invention is that effected by varying the axial relationship between two groups of these tuned coils, for example, by leaving the antenna coil and the second transformer secondary coil fixed, moving the intermediate secondary coil to 35 vary its coupling to the said first two coils commensurately with the rotation of the rotor of the variable condenser associated with this intermediate coil.

To this end the invention contemplates 40 means for varying the loose coupling between coils of two or more resonating circuits, so

that the closeness of the coupling shall vary inversely as the capacity employed in the resonating circuit. In other words, in carrying out the objective of the invention, the closeness of the coupling is automatically 55 varied inversely as to wave length or directly as to frequency. It is a still further objective of the invention to provide an adjustable mounting for some of the coils, independent from the means for varying the coupling between coils. Still further objectives of the invention are to improve in general radio receiving sets, all of which will be pointed out more in detail in the following claims which are directed to the illustrative embodiment 60 of the invention described in the following specification in connection with the accompanying drawings solely for the purpose of 65 illustration and not limitation.

In the drawings, Figure 1 is a circuit diagram of the complete receiving set. Figure 2 is a diagram showing the condenser adjustments and relative positioning of the three coils for minimum condenser value; Figure 3 is a similar diagram showing the positioning for maximum condenser value; Figure 4 is a diagram at right angles to the showing of Figure 3, showing the relative positioning for maximum condenser value. 70

In the receiving set illustrated, six triodes 75 A₁, A₂, A₃, A₄, A₅, A₆ are employed and may be connected in accordance with standard practice as indicated in the diagram of Figure 1 in which triodes A₁ to A₃ are radio frequency, and A₄ to A₆, audio frequency. In 80 the radio frequency part of the set three resonating circuits B₁, B₂, B₃ are illustrated,—B₁ for the antenna 1, B₂ for the first stage and B₃ for the second stage of amplification. In these circuits are employed respectively 85 coils C₁, C₂ and C₃, and variable condensers D₁, D₂ and D₃. Physically, coil C₁ need have but a single winding, while coils C₂ and C₃ are secondary coils of a radio frequency 90 transformer, and each is associated with a primary coil P₁ and P₂ in the usual way. In a preferred embodiment of the invention each of the coils C is wound on an appropriate tube of insulating material, and, when a primary coil is to be associated therewith, it is 95 100

preferred that such primary coil be wound upon an inserted smaller insulating tube, as common in the art. The end coils C_1 and C_3 are preferably adjustably mounted upon 5 clamps or brackets 4 which adjustably clip the tubes carrying the windings C_1 and C_2 , and may have a fixed adjustment through means of the screw nuts 5, preferably to fix the coils C_1 and C_3 so that their axes are substantially parallel and extend at about 45 degrees with the horizontal and preferably so that their axes lie respectively in the same 10 planes passing through the axes of the variable condensers D_1 and D_3 .

15 The intermediate coil C_2 is positioned preferably midway between the coils C_1 and C_3 and for minimum capacity adjustment as indicated in Figure 2 has its axis parallel to those of coils C_1 and C_3 . This coil C_2 , however, is preferably mounted upon a stem 6, forming an extension from the shaft of the variable condenser D_2 , and so as to move 20 throughout 180 degrees of rotation commensurate therewith as the condenser varies from 25 minimum to maximum capacity, and furthermore, so that the positioning of this coil C_2 will gradually change from a position of maximum coupling to minimum coupling relatively to coils C_1 and C_3 , or so that its axis 30 varies from parallelism with the end coils to a position at right angles with the axes of the end coils, as shown in Figs. 3 and 4.

In adjusting the set for best performance 35 it is sometimes found that it is best to adjust the axes of the end coils C_1 and C_3 so that they may vary a little one way or another from 45°. It is for this purpose that the adjustable clamps 4 are provided. Once the adjustment 40 is found the coils should be fixed. It is therefore to be understood that for some purposes of the invention this adjustability for the end coils is not essential but provides an easy means of properly positioning the end coils. It is further to be understood that although 45 three sets of coils for three resonating circuits are indicated, and it is the coil of intermediate position that has the rotary adjustment, this need of necessity for all purposes not be so. The middle coil might be fixed in position 50 and the two end coils rotate, but it is preferred that the intermediate coil rotate, as the mechanical structure for accomplishing the necessary adjustment is thereby simplified.

55 It is also contemplated that for all purposes it is not essential that the rotatable coil be made angularly commensurate with that of the condenser; for example only a 180 degree rotation for the coil is required while it is 60 possible that the operating shaft for the condenser might require a 360 degree rotation for varying the value of the condenser from minimum to maximum. In fact all these 65 variations in detail are contemplated as falling within the scope of this invention.

What I claim and desire to secure by United States patent rights is:

1. In a tuned radio frequency broadcast receiving set a plurality of triode tubes, a plurality of associated resonating circuits one for each stage of amplification and each comprising a variable condenser and a coil, means for varying the coupling of one of said coils with the other of said coils between a minimum and a maximum in proportion to the condenser value of the condenser adjustment of one of said variable condensers. 70

2. In a tuned radio frequency broadcast receiving set a plurality of associated resonating circuits one for each stage of amplification and each comprising a coil and one comprising a variable condenser; means for varying the relative positioning of two of said coils from a position in which their axes are substantially parallel to a relative position in which their axes are substantially at right angles contemporaneously with a variation of said variable condenser from minimum capacity to maximum capacity. 80

3. In a tuned radio frequency broadcast receiving set an assemblage of three coils mounted side by side but separated one from the other; means for adjusting the endmost coils and fixing them in a position in which their axes are approximately parallel and extend at approximately 45 degrees to the horizontal; means for adjustably rotating the intermediate coil so as to vary its position from a position in which its axis is substantially parallel to the axes of said end coils throughout an intermediate range of movement until its axis is substantially at right angles to the axes of said end coils. 90

4. The structure described in claim 3 and further characterized by the fact that a variable condenser is associated with said intermediate coil and is mechanically coupled therewith so that a single rotating element will vary said condenser from minimum capacity to maximum capacity, and at the same time vary the axes of said intermediate coil from the position of parallelism with the axes of said end coils to a position substantially at right angles with the axis of said end coils. 100

5. In a tuned radio frequency broadcast receiving set a plurality of associated resonating circuits, one for each stage of amplification and each comprising a coil and a condenser, said coils to be loosely coupled one with another for radio frequency in both; and a single means for increasing the capacity of one or more of said condensers and at the same time decreasing the coupling between said coils. 110

6. In a tuned radio frequency broadcast receiving set a plurality of associated resonating circuits, one for each stage of amplification and each comprising a coil more or less loosely coupled one with another; means for tuning said circuits comprising in addition 120

provisions for decreasing the coupling between said coils commensurately with an increase in wave length and vice versa.

7. In a multi-stage transformer coupling, 5 radio frequency system, comprising several tunable coils, one for each stage; a variable condenser including a rotor for varying the capacity reactance and in association one with each of said coils; means for operatively 10 linking one group of said coils to rotate each with its associated rotor while the remaining number of said coils are fixedly mounted, whereby the loose magnetic coupling between groups of said coils, each associated with a 15 separate stage of amplification, is varied commensurately with the rotation of said rotors.

8. A tuned radio frequency receiver comprising three triodes in a tunable grid circuit for each said triode comprising a radio frequency secondary coil and a variable condenser having a stator and a rotor variable in capacity effect by relative rotation between a maximum and a minimum capacity value; 20 means for mounting said radio frequency coils, one set in relatively fixed position and one set upon said rotors, while maintaining said coils separated and each associated with its corresponding stage, whereby electromagnetic loose coupling between said coils varies 25 between a maximum and a minimum as the capacity of said condensers varies between a minimum and a maximum.

9. A receiver as described in claim 8 and 30 further characterized by the fact that the mounting for said relatively fixed radio frequency coils is manually adjustable to facilitate an initial adjustment of the degree of loose coupling between the adjustable coil and 35 said relatively fixed coil.
